UNITED STATES PATENT OFFICE.

CHARLES ARTHUR FETTERS, OF CINCINNATI, OHIO, ASSIGNOR TO THE
C. ARTHUR NOVELTY COMPANY, OF SAME PLACE.

DESIGN FOR A GAME-CUBE.

SPECIFICATION forming part of Design No. 24,112, dated March 12, 1895.

Application filed February 7, 1895. Serial No. 537,669. Term of patent 14 years.

To all whom it may concern:

Be it known that I, CHARLES ARTHUR FETTERS, a citizen of the United States, and a resident of Cincinnati, in the county of Hamilton and State of Ohio, have invented and produced a new and original Design for a Game-Cube, of which the following is a specification, reference being had to the accompanying drawings forming part thereof.

In the drawings Figure 1 is a perspective view of my design for a game-cube. Fig. 2 represents in elevation the several faces of the same.

The leading feature of my design consists of the representation on the several faces of the cube respectively of a base-ball diamond, a bat, a ball, a glove, a mask, and a cap.

1 is the cube having the representation of a base-ball diamond on the side 2, a bat on the side 3, a ball on the side 4, a glove on the side 5, a mask on the side 6, and a cap on the side 7.

Having thus fully described my invention, the following is what I claim as new and desire to secure by Design Letters Patent—

The design for game-cube; substantially as herein shown and described.

CHAS. ARTHUR FETTERS.
